COIL WINDING MACHINE

George W. Gilman, Janesville, and Gordon F. Laing and Thomas B. Gibbs, Delavan, Wis., assignors to The George W. Borg Corporation, Chicago, Ill., a corporation of Delaware

Application November 15, 1944, Serial No. 563,522

39 Claims. (Cl. 242—9)

1

The present invention relates in general to coil winding machines and more in particular to winding machines which are adapted to wind single layer coils of resistance wire on strips of insulating material for the manufacture of rheostats and potentiometers. The object of the invention is to produce a new and improved coil winding machine of this character.

A standard strip for use in potentiometers may be made of Micarta or other suitable insulating material and may be, for example, $5\frac{3}{4}$ inches long, $\frac{7}{16}$ of an inch in width, and $\frac{3}{2}$ of an inch in thickness. The resistance wire may be "Nichrome" or any other suitable resistance wire and is usually of very small diameter. Bare wire is used and accordingly the turns of the coil or winding must be spaced apart along the strip. The strip is wound straight and after the terminals are attached it is bent to a circular formation, the strip being flexible, and is suitably mounted in the casing or frame of the potentiometer. A rotatable slider is also mounted on the frame and is adapted to engage the turns of the winding successively as the slider is rotated.

A strip wound with resistance wire as mentioned in the foregoing constitutes a resistance element and the complete assembly including the resistance element and slider constitutes a variable resistor or potentiometer. These devices have a very wide application in electrical circuits. The characteristics of the resistance element vary with the application and accordingly different lengths and sizes of wire are used. The number of turns of course varies with the length of the wire, assuming a standard strip is used, and the spacing of the turns will generally vary with the size of the wire. In a given resistance element the spacing of the turns may be uniform, meaning a constant number of turns per unit length of the resistance element, or the spacing may vary over the whole or part of the length of the resistance element. There may be, for example, a progressively decreasing spacing from one end to the other, producing a resistance element which will cause the potentiometer in which it is used to have a non-linear resistance characteristic. Non-linear rheostats and potentiometers are also made by employing resistance elements having tapered resistance wires and in

such resistance elements the spacing of the turns may be uniform or non-uniform. In case a uniform spacing is used the non-linear resistance characteristic will be contributed solely by the tapered wire, while if a non-uniform spacing is used the non-linear characteristic will be due in part to the spacing and in part to the tapered wire and results may be secured which would be difficult if not impossible with either one of these factors alone.

2
The various problems arising out of the foregoing are solved by the present invention. The coil winding machine disclosed herein is adapted to wind a large variety of coils, or resistance elements, with straight or tapered wire of any size which is suitable for the purpose, and with any desired number of turns within the limits imposed by the size of the wire and the length of the strip. The turns in the coil of any resistance element, moreover, may have either a uniform or a non-uniform spacing and if the spacing is non-uniform it may vary in any desired manner as predetermined in accordance with the desired resistance characteristic of the potentiometer in which the resistance element is to be used.

30 Another problem arises out of the fact that the resistance wire in general use for resistance elements is hard and must be wound under considerable tension in order to make the shape of the coils conform to the cross-section of the strip. The amount of tension required for this purpose depends on the size of the wire. The maximum amount of tension which can be used also depends on the size of the wire and for any given wire is greater than the tension required to form the coil, as will be obvious. However, in the case of these relatively fine resistance wires the difference between the amount of tension that can be used, as limited by the breaking strength of the wire, and the amount of tension which must be used in order to produce a tight coil is not so great as might be expected, and it follows that the tension which is suitable for one wire is sufficient to break a somewhat smaller one and is entirely unsuitable.

40 The invention takes care of the tensioning problem by a new and improved arrangement whereby the tension may be regulated or adjusted to the proper value for winding resistance wire of any size that is practicable to use. In

winding a coil with resistance wire of uniform cross-section the same tension as determined by the initial adjustment is maintained throughout the winding operation, but in winding a resistance element with tapered wire the tension is automatically changed as the winding operation proceeds and at any instant it has a value which is correct for the section of the wire which is then under tension. The new tensioning arrangement also includes means for smoothing out the variations in tension which would otherwise result from the fact that the wire is wound on a flat strip.

The foregoing and other features of the invention will be described fully hereinafter, reference being had to the accompanying drawings, in which—

Fig. 1 is a plan view of a coil winding machine embodying the invention;

Fig. 2 is a front elevation of the same;

Fig. 3 is a section on the line 3—3, Fig. 1, showing the tension adjusting mechanism;

Fig. 4 is a section through one of the collets for holding a strip during winding thereof;

Figs. 5 and 6 show a cam and supporting means thereof which is part of the tension regulating mechanism.

Fig. 7 shows a friction device for the wire spool shaft;

Fig. 8 shows the stop and catch for the guide wheel supporting arm;

Fig. 9 shows a resistance element comprising a strip of insulating material with a winding of resistance wire;

Fig. 10 shows details of the strip support and guide wheel;

Fig. 11 shows the changeable gears for driving the strip advancing cam;

Fig. 12 is a section on the line 12—12, Fig. 11;

Fig. 13 is a section on the line 13—13, Fig. 11, and

Fig. 14 is a diagrammatic circuit drawing showing the electrical connections for the motors and switches.

Referring to the drawings, the various parts of the coil winding machine are supported on a base 10, which may be the top of a table or bench. The bed 11 is preferably a steel casting and is provided with legs at the ends by means of which it is supported on the base 10. The shape of bed 11 can be seen from Figs. 1, 2 and 3.

The headstock 17 and the tailstock 18, so-called because of their resemblance to the headstock and tailstock of a lathe, are slidably mounted on the bed 11 in the usual manner and are connected together by means of the rod 19, Fig. 2, so that they always move together. This rod is threaded to enable the distance between headstock and tailstock to be adjusted. Locknuts are provided as shown.

The tailstock is provided with two integrally formed upright bearing members 20 and 21, which rotatably support the spindle 22. At its right hand end the spindle has the collet 23 for holding one end of a strip of insulating material while the same is being wound. The construction of the spindle and collet may be explained in connection with Figs. 1, 2 and 4.

The spindle 22 is tubular and is bored out at the end to a larger internal diameter to receive the collet 23. The latter is a slotted cylindrical member having an axial bore of the proper size to receive the rod 25, said bore being enlarged and provided with internal threads for a part of its length to receive the threaded sleeve 24. This

75 sleeve is made of tubular stock and has a few threads at the left hand end by means of which the nut 26 is attached. The nut 26 affords means whereby the sleeve may be rotated to engage its right hand threaded end with the internal threads of the collet 23 in order to secure the latter in position at the end of the spindle.

The rod 25 is the operating member for the pivoted latch 27 and has a sloping cam surface at the end for engaging the V shaped projection on the lower side of the latch. The latch 27 is located in a slot in the collet 23. This slot is intersected by a threaded hole having a diameter greater than the width of the slot and in which there is a spring 29 for exerting a pressure on the latch to hold it in normal position. The spring is compressed between the latch and the screw 30. The end of collet 23 is slotted as indicated at 31 and there is an insert 32 which has a corresponding slot the width of which is the same as the width of the strips to be wound. The rod 25 is normally maintained in the position in which it is shown in Fig. 4 by a spring 34. Figs. 1 and 2, which surrounds the rod between the nut 26 and the knob 33 which is attached to the end of the rod. In order to operate the latch 27 the knob 33 is pressed to the right, causing the end of the rod to engage and lift the latch, and thereby raise the pin 28 far enough so that the end thereof clears the slot 31.

The spindle 22 is driven by the gear 35 which is secured to the spindle and is in mesh with the wide faced pinion 39. The spindle is not only rotatable but is longitudinally movable also, and to effect the latter type of movement a forked lever 38 is provided, pivotally mounted on the post 40 which extends vertically upward from the tailstock. The bifurcated end of lever 38 carries two pins disposed on opposite sides of the spindle and projecting into an annular groove in the sleeve 31, which is fixed to the spindle. A spring 36 is compressed between the hub of gear 35 and the bearing member 21 and normally, that is, when no strip is in the machine, maintains the spindle in its extreme left hand position, with the shoulder 41 engaging the bearing member 21, as shown in Fig. 4. The spindle is moved to the right against the force of spring 36 by means of lever 38, as will be readily understood.

The headstock 17 is provided with the two integrally formed bearing members 42 and 43, which rotatably support the spindle 44 having the collet 45 at the left hand end thereof. The construction of spindle 44 and collet 45 is similar to the construction of spindle 22 and collet 23 just described, except that spindle 44 has no longitudinal movement in its bearings. The means for effecting such movement is omitted therefore and spindle 44 is somewhat shorter than spindle 22. For driving spindle 44 the gear 46 is provided. This gear is fixed to the spindle at a point between the bearing members 42 and 43 and is in mesh with the wide faced pinion 39. The knob 47 is for operating the latch in the collet 45 and corresponds to knob 33.

The spindles 22 and 44 and their associated collets afford means for holding a strip at its opposite ends and for rotating the strip to wind a wire thereon, as will presently be explained in detail. The wire is delivered to the strip at a fixed point past which the strip is moved lengthwise by a sliding movement of the headstock and tailstock on the bed 11. At the point where the wire is delivered additional supporting means for the strip is provided and will now be described.

Referring to Figs. 1, 2 and 10, there is a bracket 48 which spans the bed 11 and has the integrally formed bearing 49 and the two feet 50 and 51 which rest on ledges projecting from the sides of the bed. The bracket is secured to the bed by screws which pass through holes in the feet and are threaded into tapped holes in these ledges. The gear 52, which meshes with the wide faced pinion 39, is supported on the hub 53 which is rotatable in the bearing 49. Opposite the gear 52 the hub 53 supports the circular plate 54, which is held in position by machine screws passing through the gear and hub as shown. The plate 54 is the additional support for the strip and has a centrally located slot 55 in which the strip has an easy sliding fit.

The reference character 56 indicates a motor which is mounted on the base 10. The motor 56 drives the shaft 60 by means of pulleys and a belt 57, there being a plurality of pulleys of different sizes at each end of the drive to provide for rotating shaft 60 at different speeds. The shaft 60 has bearings in the two brackets 59 and 61 which are secured to the rear side of the bed 11 and extend upward for a short distance above it as can be seen in Fig. 2. The bracket 61 has a forward extension 65 at the top which provides a bearing for one end of shaft 62. This shaft has another bearing in the bracket 66 which is secured to the rear side of the bed 11 near the other end thereof. Shaft 62 is driven from shaft 60 by means of gears 63 and 64 and carries the wide faced pinion 39, hereinbefore referred to, which is adapted to rotate spindles 22 and 44 and the supporting plate 54 by means of gears 35, 46 and 52 respectively. It will be noted that the gears are all of the same size so that the spindles and supporting plate are driven in synchronism, and it will be observed further that the arrangement described provides a drive for the spindles in all positions of the headstock and tailstock.

In Figs. 1 and 2 the headstock and tailstock are shown in an intermediate position. They are movable in either direction by means of compressed air under control of the valve 67. The arrangement includes an air cylinder 70 having a piston slideable in the cylinder and a piston rod 71 which is suitably coupled to the headstock 17 as indicated. An air pipe 69 supplies compressed air to the valve 67, which has a neutral position, a left hand operated position in which compressed air is supplied to the right hand end of cylinder 70 and a right hand operated position in which compressed air is supplied to the left hand end of cylinder 70. Movement of the valve handle to the left accordingly moves the headstock and tailstock to the left and vice versa.

The limit of movement to the right is established by the engagement of the piston with the right hand end of the air cylinder. Movement to the left is limited by the cam 71, as will be explained presently. The valve 67 is so constructed that when air is admitted to either end of the air cylinder the other end of the cylinder is vented to the atmosphere by way of the exhaust valve 68. This valve is kept partly closed so as to compel a gradual exhaust of air from the cylinder and thus provide a cushioning effect to prevent the jar that would otherwise occur when the parts reach the limit of their movement in either direction.

At the left hand end of the bed 11 there is a heavy casting which is supported partly on the base 10 and partly on the bed, being secured to the latter by bolts as shown in Figs. 1 and 2.

This casting comprises the end plates 12 and 13, bottom plate 14 and the two webs 15 and 16. The shaft 62 extends to the left beyond its bearing in bracket 66 and passes through the end plate 13 of the casting, where it has another bearing. By means of a plurality of gears which will be described more in detail presently, shaft 62 drives the shaft 72, which has a bearing at the end plate 13 and another bearing 76 which is suitably supported on the bottom plate 14 as indicated in Fig. 2. Shaft 72 drives the shaft 73, which has bearings in the webs 15 and 16, by means of a worm 74 and worm gear 75. Shaft 73 supports the cam 77. The shaft is of larger diameter where it passes through the bearing in the web 16, whereby shoulders are formed against which the worm gear 75 and cam 77 are clamped by means of nuts 78 and 79, the enlarged portion of the shaft being slightly longer than the bearing to provide enough clearance so that the shaft can turn freely.

The cam 77 controls the advance of the tailstock and headstock during winding operations and to this end is provided with a follower 80 having a roller 81 engaging the periphery of the cam. The follower 80 is connected to the tailstock 18 by a rod 83 and is slidably supported on the member 82 which in turn is supported on the web 16 as shown. The follower 80 has a dovetail connection with the member 82, similar to the connection between the tailstock, for example, and the bed 11.

The gearing for connecting shaft 72 with shaft 62 may now be briefly described with reference to Figs. 11, 12 and 13.

As previously mentioned, the shaft 62 has a bearing at the end plate 13. This bearing is indicated at 89 in Fig. 12 and has a lining 90. The bearing is secured to the end plate by machine screws as shown. The gear 86 is keyed on shaft 62 beyond the bearing and is held in position by a washer and the nut 91.

The bearing 89 not only supports the shaft 62 but also forms a pivot for the sector 85, which is angularly adjustable on the bearing and is retained in any adjusted position by the stud or bolt 92 which passes through a slot in the sector 85 and is threaded into a boss on the end plate 13. The sector 85 carries two sets of gears which are supported on two adjustable studs 93 and 94. The details of the mounting of one of these sets of gears comprising gears 87 and 88 may be explained in connection with Fig. 13.

The stud 93 has a flange 99 which bears against the sector 85. Beyond this flange the stud is threaded and carries the nut 97 which is located in the slot 98. This slot is stepped and the nut comprises a shank portion which fits the narrow part of the slot and a head which fits the wide part. The nut is square so it cannot turn in the slot but it is movable along the slot to adjust the position of the stud 93. After the stud has been properly located the nut is tightened up by applying a wrench to the squared end 100 of the stud. This clamps the sector 85 between the head of the nut 97 and the flange 99 on the stud and fixes the stud rigidly on the sector.

The sleeve 95 is rotatable on the stud 93 and has a slot extending lengthwise thereof in which there is fixed a key 96. The gears 87 and 88 are carried on the sleeve 95 and have keyways for the key 96. The key and sleeve therefore effectively couple the gears together so that they 75 rotate as a unit. A suitable washer and a nut

101 prevent the sleeve 95 and the two gears from slipping off the stud.

The arrangement including stud 94 for mounting the other set of gears on sector 85 is the same as described. It will be noted that the gears shown are readily changeable for gears of larger or smaller diameter and that in any case proper meshing of the gears can be effected by adjustment of the sector 85 on its pivot and adjustment of the studs in their slots.

The shaft 72 carries the gear 102 and has a bearing supported on the end plate 13 which is similar to the bearing for shaft 62. The bearing for shaft 72 also supports the sector 103 which is similar to sector 85 and carries two sets of gears mounted on the adjustable studs 104 and 105. The arrangement will be clear from the explanation already given.

The two gear sets mounted on sector 103 are not always used. If not required to produce the necessary gear ratio between shafts 62 and 72, these gears are omitted and the inner gear stud 94 is meshed directly with the gear such as 102 on shaft 72.

The reference character 110 indicates an auxiliary base resting on the base 10 and supporting the motor 111. The auxiliary base 110 also supports a pedestal 112 which is provided near the top with suitable bearings for the shaft 113. This shaft is driven by the motor 111 through the medium of a worm on the motor shaft and a worm gear 116 on shaft 113. The drive is irreversible. At the end opposite the worm gear 116 the shaft 113 is arranged to carry a wire spool such as 115 which can be clamped against a shoulder on the shaft by a knurled nut 114.

The wire spool end of shaft 113 is shown in Fig. 7. About half way between the shoulder and the point where the threads start a transverse hole is drilled in the shaft. The drilling operation is stopped as the point of the drill breaks through, leaving an annular lip which retains the ball 117. A spring 118 is compressed between the ball and the screw 119 and tends to maintain the ball in the position in which it appears in Fig. 7. When a wire spool is placed on the shaft the ball is forced into the shaft and presses against the wall of the hole in the spool, forming a friction device which prevents the spool from spinning freely on the shaft before the nut is tightened up. The reason for the provision of this friction device will be explained presently.

The reference character 120 indicates an upright post or standard which is suitably fixed to the base 10. At the top the post 120 carries the member 121 on which the arm 122 is pivotally supported. This arm is preferably made of light wood so as to keep its weight as low as possible. The clevis 133 and the pulley 134, supported on the end of arm 122, are preferably made of aluminum for the same reason. The arm 122 is slotted at its pivoted end to provide for attachment of the metallic extension 123. The spring 124 is tensioned between the end of the extension 123 and the member 125 on post 120 and tends to rotate the arm 122 on its pivot far enough to bring the upper end of the spring into alignment with the pivot and the lower end of the spring.

The rod 130 is slidably supported by the member 125 fixed to post 120, that is, the rod has a bearing in this member in which it is longitudinally movable. At its upper end the rod 130 carries a block 129 of insulating material on which the contact springs 127 and 128 are

mounted. The spring 128 is adapted for actuation to engage the other spring by a cam member 126 which is fixed to the side of arm 122.

The lower end of rod 130 extends downward through an opening in the base 10 and is pivotally connected to one end of the lever 135. This lever is supported on the bracket 136 and has its other end pivotally connected to the rod 137, which extends upward through an opening in the base. The rod 137 is slidably supported by the bracket 138 which is mounted on the front side of the bed 11. The bracket 138 also supports a fixed post 139 which extends upward parallel to rod 137. The member 140 is slideable on post 139 and has an extension in front provided with an opening for the rod 137, the end of which is threaded for the nut 143.

The position of the member 140 on post 139 is determined by a cam 142, which is shown on a larger scale in Fig. 5. The cam is held in a slotted holder 146 by set screws, and the holder is suitably secured to the side of the headstock 17. The member 140 has a stud 145 fixed to the back thereof, which carries a roller 141. This roller rides on the cam 142. The spring 132 on rod 130 is under compression between the foot of post 120 and the collar 131 on rod 130 and applies a force to the rod which tends to move it upward. This force is communicated to rod 137 by the lever 135 and tends to move the rod 137 and the slideable member 140 downward, thereby holding the roller 141 in engagement with the cam 142. Thus the cam is able to control the position of the switch 127-128 relative to the switch actuating cam 126 on arm 122. The position of the switch determines the tension in the wire when it is wound on the strip, as will be made clear in the explanation of the operation of the machine.

The reference character 150 indicates a guide wheel for delivering the wire to the strip on which it is being wound. As shown in Fig. 3, also in Fig. 10, the guide wheel 150 is mounted on a pivoted arm 151, which in turn is supported on the bracket 48. The details of this construction are shown in Fig. 10, from which it will be seen that the shaft 153, on which the guide wheel 150 is mounted, is supported on the arm 151 by means of ball bearings. These bearings should be carefully adjusted for free rotation of wheel 150 but without play in the bearings. The arm 151 is supported by ball bearings on the flanged stud 154 which passes through the bracket 48 and is held in place by a nut. The stud is squared at the end so that it can be held by a wrench while the nut is being tightened up. A helical spring 155 has one end secured to the arm 151 and the other end secured to the stud 154 and is tensioned to rotate the arm in a counter-clockwise direction as seen in Fig. 3. If a strip is in the machine the spring 155 holds the guide wheel against the strip. If no strip is in the machine the movement of the arm 151 is arrested by a stop 156 formed on the block 157 located between arm 151 and bracket 48 and secured to the latter by a machine screw. The tension in spring 155 is adjusted by loosening the nut on the stud 154 and turning the stud in one direction or the other until the spring has the proper tension. The nut is then tightened up to hold the stud in adjusted position.

The block 157 has a hole drilled therein to receive the latch 158 and has a slot for the operating pin 160 which is secured to the latch. The spring 159 is compressed between the pin 160 and the bracket 48 and forces the latch to the left,

Figs. 8 and 10, as far as such movement is permitted by pin 160. The latch is provided to hold the guide wheel 150 out of the way while a strip is being inserted in the machine. When the arm 151 is pulled forward it becomes engaged by the latch in an obvious manner and later on is released by moving the operating pin to the right.

As shown in Fig. 3, the arm 151 has a forward extension 152 which carries the pulley 161.

The guide wheel 150, arm 151 and extension 152 are made as light as possible consistent with the necessary strength, to enable the guide wheel to maintain contact with the strip during the winding operation. The rotation of the strip causes the arm 151 to oscillate on its bearing and by keeping the inertia of the arm and associated parts low the requisite movement is made possible with only a moderate tension in spring 155.

At the rear of the bed 11 two brackets 165 and 166 are attached and project horizontally to the rear. The rod 167 is slidably supported in these brackets and carries the two adjustable collars 168 and 169. A switch comprising the contact springs 171 and 172, Fig. 14, and enclosed in the housing 173, is secured to the end of the bed 11 and is adapted to be operated by the rod 167. The rod is moved to the right and left by means of a member secured to the tailstock 18 and having a depending projection 170 which is adapted to engage the collars 168 and 169 on rod 167. Near the end of the movement of the tailstock to the left the projection 170 engages the collar 168 and moves the rod 167 to the left to open the switch. To avoid any danger of damaging the switch the rod 167 has a spring biased retractable pin 174 at the end for engaging the switch actuating member. The switch is self-closing and in order to prevent it from closing at once when the tailstock starts to move to the right a friction device in the form of a spring 175 bearing on rod 167 is provided. When the tailstock reaches nearly the limit of its movement to the right the projection 170 engages the collar 169, which moves the rod 167 to the right and permits the switch to close.

The wiring of the machine is shown in Fig. 14. The motors 56 and 111 may be alternating current motors of known type. The circuit of motor 56 includes the hand operated switch 181 and the switch 171-172, these switches being in series. The circuit of motor 111 is similar and includes the hand operated switch 180 and the switch 127-128. The hand operated switches are mounted at a convenient point on the base 10, as shown in Fig. 1.

A seat is provided for the operator and is preferably located in front of the machine as it appears in Fig. 1 and about in line with the motor 111. The parts of the machine which have to be attended to are thus directly in front of the operator and the valve 67 and switches 180 and 181 can easily be reached with her right hand.

The operation of the machine will now be described. For this purpose it will be assumed that the machine is set up for winding standard strips with tapered resistance wires. The resistance wires are supplied on spools such as 115. Each spool contains one tapered resistance wire wound on the spool in a single layer.

In Figs. 1 and 2 the machine has been shown with the headstock and tailstock at approximately the center of their travel on the bed, but this has been done to avoid obscuring the collet 45 on spindle 44, which in the normal position of the machine is inside the hub 53 on which the

gear 52 is supported. From this it will be understood that the machine normally stops with the headstock and tailstock assembly in its extreme left hand position. The machine has also been shown with a strip held in the collets, although the insertion of the strip has not been explained. The strips are changed in the normal position of the machine.

In order to advance the machine to normal position the operator may move the handle of valve 67 to the left and close the switch 181. The operation of the valve admits compressed air to the right hand end of air cylinder 70, thereby applying a force to the headstock and tailstock assembly which tends to move it to the left. Such movement is prevented by cam 77, but the air pressure holds the roller 81 of follower 80 against the cam. The closure of switch 181 starts the motor 56 which drives the shaft 60 by means of belt 57. Shaft 60 drives the shaft 62 through the medium of gears 63 and 64 and shaft 62 drives the cam shaft 73 by means of gears 86, etc., shaft 72, worm 74 and worm gear 75. Shaft 62 also drives the spindles 22 and 44 by means of the wide faced pinion 39, also the support 54, but the operation of these parts may be neglected for the moment as the operator is merely engaged in advancing the machine to normal position.

The cam shaft 73 is rotated in a clockwise direction as seen in Fig. 2, and the cam 77 accordingly permits the headstock and tailstock assembly to move gradually to the left, under the air pressure in cylinder 70. This movement continues until the projection 170 on the tailstock 18 engages the collar 168 on rod 167 and moves the rod to the left to open the switch 171-172 and stop the motor 56. When the machine stops the cam 77 will have rotated about 180 degrees from the position in which it is shown in Fig. 2.

The strip 185 is inserted from the left as seen in Figs. 1 and 2. One end of the strip is passed through the slot 55 in the intermediate supporting plate 54 and into the slot at the end of collet 45 on spindle 44. These slots are in angular alignment. As the strip enters the collet the end of the strip engages the sloping end of the pin at the end of the latch (see Fig. 4 for the corresponding parts of collet 23) and raises the pin and latch by a cam action. The strip thus passes beneath the pin, which drops into the hole in the strip as soon as the hole comes into alignment with it, thereby locking the strip against withdrawal from the collet. The other end of the strip is now just outside collet 23. To cause the strip to enter the collet 23 the operator grasps the lever 38 and moves it to the left, thereby moving the spindle 22 and collet 23 to the right. At the same time the end of the strip is guided into the slot at the end of the collet. As the collet 20 moves to the right the pin 28 slides up on the strip and then drops into the hole in the strip. The operator now releases the lever 38, whereupon the spindle is returned toward the left by spring 36 far enough to take up the slack, if any, in the connections between the strip and the collets. The strip is now held between the two collets and is under tension produced by the force of the compressed spring 36.

It should be stated that before starting to insert the strip as described in the foregoing the operator will pull the arm 151 forward to get the guide wheel 150 out of the way. The arm 151 is locked in its forward position by the latch 158.

The operator may now swing the handle of valve 67 to the right, which admits compressed

air to the left hand end of cylinder 70 and connects the right hand end of the cylinder with the exhaust valve 68. As the result the headstock and tailstock assembly is moved quickly to the right as far as it can go, or until the piston engages the end of the cylinder. The gradual exhaust of air from the right hand end of the cylinder maintains sufficient back pressure to prevent excessive shock when the movement is arrested. As the headstock and tailstock assembly approaches the end of its movement to the right, the projection 170 on the tailstock engages the collar 169 on rod 167 and moves the rod to the right, thereby releasing the switch 171—172 and permitting it to restore to its normal closed position.

The closing of switch 171—172 restarts the motor 56 and the machine starts to run again as previously described. In the movement of the headstock and tailstock assembly to the right the follower 80 moves to the right also, of course, the follower being attached to the tailstock. The distance through which the parts move to the right is slightly greater than the rise on the cam 71, and it will be understood therefore that in the right hand position now occupied by the follower 80 the roller 81 is out of the way of the high end of the cam. In this connection it should be pointed out that the collar 169 should be so adjusted that the motor circuit is not closed until the necessary clearance has been effected.

The starting position is indicated by an arrow on the cam. The operator watches the cam as it rotates and as soon as the arrow reaches a position in alignment with the center of the roller 81 she stops the machine by opening the switch 181. In case of overrun, or error in operating the switch, the cam can be brought to the correct position by means of the hand wheel 58, but a practiced operator has no difficulty in stopping the machine properly so that no adjustment is necessary. The angular distance between normal position and starting position depends on how much of the cam is used. Assuming that 340 degrees of the cam are used, then the distance is 20 degrees.

The operator may now swing the handle of the valve 67 to the left, admitting compressed air to the right hand end of the cylinder 70 and moving the headstock and tailstock assembly to the left. The movement is short and is stopped by the roller 81 engaging the cam 71.

If not already done the operator now takes a spool 115 containing a tapered resistance wire and places the spool on the shaft 113. The nut 114 is put on also but is not tightened up, leaving the spool free to rotate on the shaft except for the friction device described in connection with Fig. 7.

The resistance wire usually includes an end section several feet long which is of uniform diameter, then a tapered section in which the cross-section of the wire progressively decreases according to some predetermined formula or equation, and finally another end section of uniform diameter. In winding the wire on a strip the winding is started with the large end of the wire. During the manufacture of the wire the large end section is marked with paint or in any suitable manner to advise the operator of the winding machine where to start to wind. This mark is placed at the proper distance from the beginning of the tapered section to insure that the tapered section will be properly located on the strip when the winding is completed.

The ends of the resistance wire may be secured in notches in the flanges or heads of the spool. After detaching the large end of the wire, the operator pulls the wire off the spool until she finds the mark and then cuts the wire off at this point. The part cut off is discarded. The wire is then passed over the pulley 134 and the end is secured to the collet 23 by means of a small spring clip 186, shown in Fig. 4. During this operation the necessary amount of wire is drawn off the spool but only as much as required is unwound, due to the friction device which prevents free rotation of the spool. The operator now operates the machine by means of the hand wheel 58, rotating the strip 185 to wind on a few rather widely spaced turns. The hand wheel is rotated with one hand and with the other hand the operator guides the wire onto the strip. Three or four turns will be sufficient to bring the wire to a point on the strip which is opposite the guide wheel 150. The operator now places the wire on the guide wheel 150 and pulley 161 and turns the spool 115 back enough to take up the slack. The wire, indicated at 187 in Fig. 3, passes from the strip 185 over the guide wheel 150 and under the pulley 161. The guide wheel and pulley are grooved. After the operator has seen to it that the wire is properly located in the grooves and has taken up any slack that may be present so that the wire cannot become dislodged she can tighten up the nut 114 to secure the spool 115 to the shaft 113 on which it is supported.

The operator may now move the latch 158 to the right by means of pin 160 to release the arm 151 on which the guide wheel 150 is mounted. Arm 151 accordingly is rotated on the stud 154 by spring 155 to bring the guide wheel against the strip. The machine is now ready to start winding the wire on the strip but before proceeding with the explanation it will be advisable to direct attention to the condition of the wire tensioning means.

Since the machine is in starting position the headstock and tailstock assembly is displaced to the right from the position in which it is shown in Fig. 2 and the cam 142 likewise, with the result that the roller 141 is now resting on the high horizontal part of the cam rather than on the sloping portion thereof. The rod 137 is therefore raised and the rod 130 is correspondingly lowered from the position in which these parts appear in Fig. 3. In view of the position of rod 130, the block 129 and the switch 127—128 which are supported on the rod are also in a lower position. The exact position of these parts at this time depends on the adjustment, which is effected by means of nut 143 on rod 137, as will be explained presently. It will be sufficient for present purposes to state that at the start the switch 127—128 is low enough so that the arm 122 has to rotate on its pivot a substantial amount from the horizontal, say 15 or 20 degrees, in order to close the switch. As regards the present position of this arm, if the operator has merely taken up the slack in the wire, the end of the arm will be elevated due to the tension in spring 124 and the lever extension 123 will be substantially parallel with the post 120. The operator may be instructed, however, to tighten up the wire enough so as to bring the arm 122 substantially to a horizontal position. The spring 124 will therefore supply a certain amount of initial tension to the wire.

In further explanation of the cam 142 it will be understood that the sloping section of the cam

corresponds to the tapered section of the resistance wire. The base of this sloping section of the cam is equal or substantially equal in length to the section of the strip 185 on which the tapered section of the wire is to be wound, and the cam is so adjusted lengthwise relative to its support that when the machine is winding the tapered section of the wire on the strip the roller 141 will bear on the sloping section of the cam.

Proceeding with the explanation of the winding operation, the operator should close the switch 180 in the circuit of motor 111, if this switch is not already closed. The motor does not start, however, since the switch 127-128 is open. The operator may now close the switch 181, which starts the motor 56, switch 171-172 now being closed. The machine now starts to run. The two spindles 22 and 44 and the supporting plate 54 are rotated simultaneously and positively rotate the strip 185 to wind the wire 187 thereon in successive turns, while at the same time the cam 11 rotates slowly to control the advance of the headstock and tailstock assembly to the left and thus space the turns apart on the strip. The winding speed may be about 350 turns per minute.

When the winding starts, the wire for the first couple of turns or so is necessarily taken from the loop which extends upward to pulley 134 at the end of arm 122, since the spool 115 cannot rotate the motor 111, and the shortening of this loop draws the pulley 134 downward, thereby rotating arm 122 on its pivot. The rotation of the arm results in further tensioning of the spring 124, and since the force required to produce the rotation is applied through the wire, it is placed under an increasing tension as the rotation of the arm takes place. The rotation of the arm continues for a few degrees, as explained hereinbefore, until the cam 126 engages the spring 128 and forces it into contact with spring 127. This operation closes the circuit of motor 111 which begins to run and rotate the spool 115, thereby feeding the wire off the spool and relieving the tension in the wire sufficiently to prevent further rotation of the arm 122.

The demand for wire varies periodically at the winding frequency, due to the fact that the wire is being wound on a flat strip. The periodic variation in the demand for wire causes the arm 122 to vibrate during the winding operation and the cam 126 alternately closes and opens the switch 127-128, which automatically regulates the speed of motor 111 to maintain the proper tension in the wire. If at a certain instant the motor runs a little too slow, for example, producing too much tension in the wire, the average position of arm 122 is lowered slightly, thereby increasing the ratio of the time during which the switch is closed to the time during which it is open and increasing the amount of power delivered to the motor. The motor therefore increases its speed, feeds out the wire faster, and the tension is decreased. If this action proceeds too far, it is corrected by the resulting change in the average position of arm 122, which causes the power supplied to the motor to be cut down, as will be readily understood.

The wire is delivered to the strip by the guide wheel 150, which maintains contact with the strip during the winding operation. It will be understood, therefore, that the guide wheel has an oscillatory motion. The guide wheel is pressed against the strip by the spring 155, aided by the tension in the wire. As regards the effect of the wire tension it will be seen from Fig. 3 that the

5 pulley 161 is located somewhat to the right of an imaginary line drawn between the pivot of arm 151 and the point where the wire leaves the pulley 134, and that as the result of this arrangement the tension in the wire will apply a force to the arm 151 which is cooperative with the force exerted by the spring.

The strip is supported close adjacent the guide wheel by the plate 54. The plate is driven in synchronism with the spindles and thus helps to rotate the strip, but the spindles alone bring about the longitudinal movement of the strip, which slides in the slot in the plate as the winding proceeds. The firm support which the rotating plate 54 affords to the strip at the point where the wire is delivered is a large factor in the successful operation of the machine.

As explained before, the winding is started at a certain predetermined point on the large end section of the wire, the unused portion of which is cut off. The remainder of this end section, which may be a foot or more in length, is wound on the strip first, followed by the tapered section, which may be fifty feet or more in length. During the time that the end section of the wire is being wound on the strip the roller 141 rides on the high horizontal part of the cam 142 and a uniform strong tension is maintained on the wire. As the winding proceeds the cam moves to the left under the roller and as the winding of the tapered section of the wire begins the sloping portion of the cam reaches the roller. From now on and until the winding of the tapered section is completed the roller rides on the sloping portion of the cam, with the result that the tension on the wire is gradually decreased.

40 The decrease in the tension is caused by the raising of the switch 127-128, through the medium of its connection with roller 141, and the resulting counter-clockwise rotation of the arm 122, which decreases the tension in spring 124. The tension on the wire is always equal to one half the force exerted by the spring, as measured at pulley 134. The decrease in the wire tension is approximately proportionate to the decrease in the cross-section of the tapered wire and to its breaking strength.

When the winding of the tapered section of the wire has been completed the machine starts to 55 wind the small end section and at this time the roller 141 begins to ride on the low horizontal part of cam 142. From this point on therefore the tension on the wire does not change.

When the required number of turns of the small 60 end section have been wound on the strip the machine is stopped by the opening of switch 171-172 as previously described, which opens the circuit of motor 56. The motor 111 stops an instant later, or as soon as enough wire has been fed off the spool to relieve the tension sufficiently so that the switch 127-128 remains open.

The operator may now cut off the wire a few 65 inches from the strip and detach the starting end from the clip 186 on the collet 23. In order to release the strip from the collet the operator moves the spindle 22 slightly to the right by means of the lever 38 and then presses the knob 33 to the right to raise the latch in the collet. While the knob 33 is held in operated position the lever 70 is released, whereupon the spindle is moved to the left by spring 36 until the shoulder 41 engages the side of bearing 21. The left hand end of the strip is now outside the collet. The operator now momentarily presses the knob 47 to 75 the left to raise the latch in collet 45 and removes

the wound strip from the machine. The ends of the winding are suitably secured, as by looping them through the holes at the ends of the strip or by the application of a spot of adhesive. This finishes the strip insofar as the winding thereof is concerned. The operator may now insert another strip in the manner explained and shift the handle of the air valve 67 to the right. The headstock and tailstock assembly accordingly moves to its right hand position and closes the switch 171-172, which starts the motor 56 to advance the machine to starting position.

While waiting for the machine to reach its starting position the operator may remove the spool 115 from which the wire just wound has been taken and replaced it with another spool containing another resistance wire.

When the machine reaches its starting position, as indicated by the mark on the cam 77, the operator stops the machine as before by opening the switch 181. The air valve handle is now moved to the left to bring the roller 81 of follower 80 against the cam. The operator now passes the end of the new resistance wire over pulley 134 and attaches it to the collet 23 by means of clip 186, then loops the wire over the guide wheel 150 and under the pulley 161, takes up the slack in the wire and secures the spool by means of nut 114, all as previously explained. During these operations the switch 180 may remain closed, since the circuit of motor 111 is open at switch 127-128. The winding of the second strip is now ready to proceed and is started by closing the switch 181. The operation from now on is a repetition of the operation performed in winding the first strip and will require no further explanation.

The general appearance of the wound strips is shown in Fig. 9, where 185 indicates a strip of insulating material and 187 indicates a resistance wire wound thereon. The drawing is not intended to show the size of the wire nor the actual number of turns or spacing thereof. It does, however, indicate a progressively decreasing spacing of the turns. The wire may be tapered or of uniform diameter throughout its length, although in the present case a tapered wire has been assumed. The machine is adapted to wind very fine wire, and coils have been successfully wound using un-tapered wire as small as .9 mils in diameter. This is about the smallest size wire that it is practicable to make. Tapered wires may be 6 or 8 mils or larger at the large end and may be as small as .9 mils at the small end, with any form of taper. The number of turns which can be wound on a given strip depends on the spacing of the turns, and on the size of the wire. A strip wound with wire .9 mils in diameter may have 500 or more turns per inch.

Some further explanation regarding the setting up and adjustment of the machine may now be given. The most complicated case to be considered involves the winding of a resistance element for a non-linear potentiometer having a resistance curve which requires the use of a tapered resistance wire and a non-uniform turn spacing which supplements or modifies the effect of the taper.

In order to wind a resistance element such as described above the cam 77 must be of special design, adapted to produce the required spacing. A suitable procedure for making the cam will therefore be explained briefly.

In a typical case which will be assumed by way of example, the specification covering the poten-

tiometer gives the length of the resistance element, that is, the length of the winding, the total resistance of the resistance wire, and the resistance of each of 20 imaginary sections of equal length into which the winding is divided for the purpose of defining its resistance characteristic.

The first step is to obtain the data on the resistance wire which is to be used. The resistance of this wire must be, of course, equal to the specified resistance. The data required includes information as to the length of the wire and a resistance curve or the equivalent which shows the exact form of the taper.

From the resistance curve of the wire to be used 15 and the specified resistances of the winding sections the length of wire in each section is calculated. The length of a turn is known from the size of the strip, which enables the number of turns in each section to be calculated from the 20 length of wire in such section. The total number of turns in the winding is also calculated from the length of the wire and the known length of a single turn.

The next step is to divide the working portion 25 of the cam into 20 imaginary sections corresponding to the winding sections and calculate the number of degrees in each cam section from the number of turns in the corresponding winding section. In this connection it will be evident 30 that since the cam is geared to the spindles which rotate the strip the number of degrees in any cam section will be proportionate to the number of turns in the corresponding winding section. Any desired part of the cam can be used, up to about 35 350 degrees, but 340 degrees is the amount generally used. Dividing the total number of turns by 340 gives the number of turns per degree, and dividing the number of turns in any winding section by the turns per degree will give the degrees in the corresponding cam section.

Now the total rise on the cam over the working portion thereof, 340 degrees, is equal to the length of the winding, which is known. Dividing the total rise by 20 the rise per section is obtained.

45 The information now at hand as to the length in degrees of each of the 20 sections which make up the 340 degree working portion of the cam and the further information as to the rise per section enables the designer to fix 20 points on 50 the cam, in addition to the starting point, and this will usually be sufficient to enable him to lay out the entire contour of the cam.

For winding coils having uniformly spaced turns a straight line cam is used, the design of 55 which presents no difficulty. In a straight line cam there is a uniform rise per degree over the whole working portion of the cam.

The gear ratio is obtained by dividing the total 60 number of turns in the winding by the number of rotations of the cam. The cam always makes less than one complete rotation, and in the assumed case rotates 340 degrees. So the number of turns is divided by the fraction 340 over 360 to obtain the total speed reduction required. Shaft 62 rotates at the same speed as the spindles, but there is a 100 to 1 reduction between shaft 65 72 and shaft 73. The total speed reduction is therefore divided by 100, and the result gives the speed reduction which must be obtained between shafts 62 and 72 by means of the gears 86, 87, etc. The machine is supplied with sufficient gears of various sizes so that by interchanging gears the desired reduction can be obtained.

The starting point for the machine is marked 75 on cam 77, as previously mentioned. The ma-

chine is set to stop at the right point by running it from the starting point and counting the number of rotations of shaft 82 with a rotation counter. Prior to this operation the collar 168 on rod 167 is loosened up so that the rod cannot be operated to stop the machine. When the counter indicates a number of rotations which is equal to the number of turns in the winding the machine is stopped manually by opening the switch 181 and the collar 168 is adjusted and locked on rod 167 in the correct position so as to just barely open switch 171-172.

The rise on the cam 142 depends on various factors involved in the design of the wire tensioning mechanism, such as the lever ratio in the linkage, the length of arm 122, etc., and is preferably determined by experiment. It will be understood, however, that the rise will be at least roughly proportionate to the taper on the wire, that is to the difference between the large and small diameters of the wire. For example, a greater rise will be required for a wire which tapers from .8 mils to .9 mils than for one which tapers from .5 mils to .9 mils.

The contour of the cam should conform generally to the contour of the taper. If the taper is conical or not too far from conical the contour of the cam may be a straight line. The square ratio between the diameter of the wire and its cross section or breaking strength is taken care of by the design of the lever arrangement for operating the switch 127-128, including the spring 124. This part of the apparatus is so designed that within the operating range of arm 122 (about 45 degrees) the force required to rotate the arm from its uppermost or zero position to any new position is approximately proportionate to the square of the distance from the zero position to the new position.

The wire tension is preferably adjusted before winding starts and before the first wire is attached to the machine. For this purpose the proper amount of tension for wires of different sizes is determined experimentally or by calculation, and weights of corresponding value are provided. In the case of a tapered wire the wire tension employed most nearly approaches the breaking strength of the wire at the small end, there being a considerably greater factor of safety at the large end, and the tension adjustment is accordingly made in accordance with the small diameter of the wire. In order to make the adjustment the headstock tailstock assembly is shifted to its left hand position, if not already there, to cause the roller 141 to ride on the low horizontal part of cam 142. The appropriate weight is then hung on the end of arm 122 and the nut 143 on rod 137 is adjusted up or down until the cam 126 just barely closes the switch 127-128. When the adjustment is finished the weight is removed.

The invention having been described that which is believed to be new and for which the protection of Letters Patent is desired will be pointed out in the appended claims.

We claim:

1. In a coil winding machine, means for holding and rotating a strip adapted to form a support for a coil, means for delivering wire to said strip at a fixed point to form a coil on the strip responsive to its rotation, and means for progressively advancing said holding and rotating means to move said strip past said fixed point in timed relation to the rotation of the strip in order to space the turns of the coil.

2. In a coil winding machine, means for holding and rotating a flexible strip of material, a rotatable support for said strip fixed against movement lengthwise of the strip, means for delivering wire to said strip at a point adjacent to said support to form a coil on the strip responsive to its rotation, and means for moving said holding means to thereby advance said strip longitudinally relative to said support to space the turns of the coil.

3. In a coil winding machine, two devices for holding a flexible strip of material at its opposite ends, respectively, a supporting device for said strip located at a point intermediate of said holding devices, and means for positively driving all said devices at the same speed.

4. In a coil winding machine, two shafts in axial alignment, means at the adjacent ends of said shafts for holding a flexible strip of material at the opposite ends thereof, a rotatable device for supporting said strip at a variable point intermediate of the ends thereof, means for positively driving said shafts and said device at the same speed, and means for axially moving said shafts independent of said device to change the point at which the strip is supported by the device.

5. In a coil winding machine, means for holding and rotating a strip of material adapted to form a support for a coil, means including a guide wheel for delivering wire to said strip to wind a coil thereon responsive to rotation of the strip, means for pressing said wheel against said strip during the winding of said coil, and means for moving said strip past said wheel to space the turns of said coil.

6. In a coil winding machine means including two spindles in axial alignment for holding and rotating a strip of material to wind a coil thereon, supporting means for said spindles, said supporting means being movable to produce axial movement of said spindles, a fluid operated actuator for said supporting means, and means including a cam rotating in timed relation to the rotation of said spindles for controlling the speed with which said supporting means moves under the power supplied by said actuator.

7. In a coil winding machine, a device for holding and rotating a strip of material to wind a coil thereon, a support for said device, means for moving said support to space the turns of said coil, and means responsive to a predetermined movement of said support for stopping the rotation of said device.

8. In a coil winding machine, a device for holding a strip of material adapted to form a support for a coil, a motor for rotating said strip to wind said coil thereon, a movable support for said device, means driven by said motor for controlling the movement of said support to space the turns of said coil, and a switch actuated by movement of said support to control the circuit of said motor.

9. In a coil winding machine, means for holding and rotating a strip adapted to form a support for a coil, means for delivering a wire to said strip to form a coil on the strip responsive to rotation thereof, means for longitudinally moving the strip relative to the point at which the wire is delivered to space the turns of the coil, and means for automatically changing the speed at which the strip is moved to vary the spacing.

10. In a coil winding machine, means for holding and rotating a strip adapted to form a sup-

port for a coil, means for delivering a wire to said strip to form a coil on the strip responsive to rotation thereof, said wire being tapered, means for axially moving the strip relative to the point of delivery of the wire to space the turns of the coil, and means for automatically changing the rate at which the strip is moved to produce a non-uniform spacing which bears a predetermined relation to the taper on the wire.

11. In a coil winding machine, means for holding and rotating a strip adapted to form a support for a coil, means for delivering a wire to said strip to form a coil on the strip responsive to rotation thereof, means for axially moving said strip relative to the point of delivery to space the turns of the coil, and means for progressively slowing down the rate of axial motion of the strip while maintaining the rotational speed constant, thereby progressively increasing the number of turns per unit length along the coil.

12. In a coil winding machine, means for winding a tapered wire on a strip to form a coil having a plurality of spaced turns, means for placing said wire under tension at the start of the winding operation, and means for automatically varying the tension in accordance with the change in the size of the wire as the winding proceeds.

13. In a coil winding machine, means for holding and rotating a strip of material, means for delivering a tapered wire from a spool to said strip to form a coil on the strip responsive to rotation thereof, and means for maintaining a varying tension in that section of the wire which extends between the spool and the strip which at any instant is proportionate to the size of the wire in said section.

14. In a coil winding machine, means for winding a tapered wire on a strip to form a coil having a plurality of spaced turns, said coil being started with the larger of the two ends of the wire, means for placing the wire under an initial tension which is appropriate for the larger end of the wire but excessive for the smaller end, and means for automatically decreasing the tension as the winding proceeds.

15. In a coil winding machine, a device for holding and rotating a strip of material adapted to form a support for a coil, means for delivering a tapered wire to said strip to wind a coil thereon responsive to rotation of the strip, a support for said device, means for moving said support in timed relation to the rotation of the strip to space the turns of the coil, means responsive to rotation of the strip for placing the wire adjacent thereto under tension, and means including a cam moving with said support for varying the tension.

16. In a coil winding machine, means for holding and rotating a strip to form a coil thereon from a wire contained on a spool, means for preventing said first means from rotating said spool by pulling on said wire, means for rotating said spool to permit said wire to be unwound from the spool as it is wound on the strip, and means responsive to tension in said wire for controlling said rotating means.

17. In a coil winding machine, means for holding and rotating a strip to form a coil thereon from a wire contained on a spool, means for preventing said first means from rotating said spool by pulling on said wire, means including a motor for rotating said spool to permit said wire to be unwound from the spool as it is wound on the strip, means for placing the wire between the spool and strip under a varying tension which increases responsive to rotation of the strip and 75

decreases responsive to rotation of the spool, and means responsive to a predetermined tension for closing the circuit of said motor.

18. In a coil winding machine, means for holding and rotating a strip to form a coil thereon from a wire contained on a spool, means including a motor for rotating said spool, an actuator subject to vibration responsive to the varying pull on the wire produced by rotation of the strip, and a switch intermittently closed and opened by said actuator at its vibration frequency to supply power to said motor.

19. In a coil winding machine, means for holding and rotating a strip to form a coil of wire thereon, means including a motor for feeding the wire to said strip, a pivoted arm arranged to be rotated by the pull on the wire as it is wound on said strip, a spring opposing rotation of said arm to tension said wire, a switch operated responsive to rotation of said arm to start said motor, and means for changing the relation between said switch and said arm to regulate the tension produced in said wire by said spring.

20. A non-linear resistance element comprising a strip of insulating material having a winding of tapered wire, said wire being under tension, and the degree of tension at different points along said element being proportionate to the size of the wire at such points.

21. The method of winding a tapered resistance wire on a strip to form a resistance element, which consists in rotating the strip to wind the wire thereon, feeding the wire to the strip at a limited rate, applying a force to the section of wire between the strip and feeding means to place such section under tension, and adjusting the force to change the tension in accordance with the change in the size of the wire in such section as the winding operation proceeds.

22. The method of winding a tapered resistance wire on a strip to form a resistance element, which consists in rotating the strip to wind the wire thereon, feeding the wire to the strip at a fixed point, moving the strip longitudinally with reference to said point to space the turns of the winding, and changing the rate of said longitudinal movement with respect to its rotational speed to produce a varying spacing which bears a predetermined relation to the slope of the taper on the wire.

23. The method of winding a resistance wire on a strip to form a resistance element, which consists in rotating the strip to wind the wire thereon, feeding the wire to the strip at a limited rate, maintaining a loop in the wire between the strip and feeding means, opposing an increasing force to the shortening of the loop which results in case the demand for wire by the rotating strip exceeds the rate of feed, thereby maintaining the wire in the loop under a tension which is proportionate to the length of the loop, and increasing the feed if the tension becomes greater than a predetermined value.

24. In a coil winding machine, means for holding and rotating a supporting element for a coil, means for delivering wire to said element to form a coil thereon responsive to rotation thereof, spacing means including a cam and follower for controlling movement of said holding and rotating means to advance said element past the point where the wire is delivered thereto, and means for driving said cam at a speed which bears a predetermined relation to the rotational speed of said element.

25. In a coil winding machine, a base, a device slidably mounted on said base, means in said device for holding and rotating a supporting element to wind a coil thereon, means including a cam for controlling the sliding movement of said device, means for rotating said cam in timed relation to the rotation of said element, and means responsive to the arrival of said device in a predetermined position for stopping the rotation of said element.

26. In a coil winding machine, a device for holding a supporting element for a coil, means including a cam for controlling movement of said device to cause a longitudinal movement of said element, means for rotating said cam, means in said device including a spindle geared to said cam for rotating said element to wind a coil thereon in spaced turns, means for stopping the rotation of said spindle responsive to a predetermined extent of movement of said device, and means for readily changing the gear ratio between said cam and spindle to enable the machine to wind coils which differ as to the number of turns contained therein.

27. In a coil winding machine, means for winding a wire on to a supporting element to form a coil thereon having a plurality of spaced turns, and means operated in timed relation to the progress of a winding operation for controlling the spacing of said turns to produce a varying spacing which is independent of the wire size and which is greater in one section of said coil than in an adjacent section.

28. In a coil winding machine, means for winding a wire on to a supporting element to form a coil thereon, and means for spacing the turns of said coil apart as the coil is wound, said means including an element which is adapted to produce a predetermined varying spacing and which is readily interchangeable with a similar element adapted to produce a different predetermined varying spacing.

29. In a coil winding machine, means for winding a wire on to a supporting element to form a coil on the element having a plurality of turns, wire guiding means for delivering the wire to said element, means for producing a relative movement between said element and guiding means to space said turns, and means including a cam for controlling said movement, said cam having an operative contour which is effective to produce a spacing which varies from turn to turn according to a predetermined law.

30. In a coil winding machine, means for winding a length of tapered wire on a support to form a coil having a plurality of turns, means for placing a section of said wire adjacent said support under tension during the winding operation, and means including a cam having a rise corresponding to the slope on said wire for automatically regulating the tension in accordance with the size of the wire in said section.

31. In a coil winding machine, means for winding a tapered wire on a support to form a coil having a plurality of turns, means for placing a section of said wire adjacent said support under tension during the winding operation, and means operated in timed relation to the progress of the winding operation for regulating the tension in said section in accordance with the size of the wire therein.

32. In a coil winding machine in which coils are wound from wire contained on a spool, a motor, an irreversible driving connection between

said motor and said spool, whereby said motor can drive said spool but said spool cannot drive said motor, a circuit for said motor, and means responsive to a predetermined pull on the wire by operation of said machine for closing said circuit.

33. In a coil winding machine, means for holding and rotating a supporting element to wind a coil thereon from wire contained on a spool,

10 means for forming a loop in the wire between said element and spool, said means including a lever having one arm to which a force is applied by the wire in said loop, a spring adapted to apply an opposing force to another arm of said lever,

15 said lever and spring being so arranged that the ratio of the spring arm to the loop arm of the lever increases responsive to rotation of the lever on its fulcrum, and means actuated by rotation of said lever for controlling the rotation of said spool to feed the wire.

34. In a coil winding machine, means for winding a wire on to a support from a supply spool to form a coil on the support, a motor for rotating said spool to feed the wire off the spool, means

25 including a switch for supplying power to said motor, a switch actuator movable toward said switch by tension in said wire between said support and spool, a spring opposing such movement, and means for adjusting the position of said switch relative to said actuator to enable the switch to be closed responsive to a selected wire tension.

35. A coil winding machine as claimed in claim 34, wherein means is provided for automatically changing the position of said switch to vary the wire tension during a winding operation.

36. The method of winding a resistance wire on a core or support to form a resistance element,

40 which consists in rotating said support to wind the wire thereon, feeding the wire to the support at a fixed point, moving the support longitudinally with reference to said point to space the turns of the winding, and changing the rate of

45 the longitudinal movement of said support with respect to its rotational speed to produce a varying spacing which gives said resistance element a non-linear resistance characteristic.

37. In a coil winding machine in which coils

50 are wound from wire contained on a spool, a motor, an irreversible driving connection between said motor and spool, whereby said motor can drive said spool but said spool cannot drive said motor, and means for regulating the speed of said motor in response to changes in the pull on said wire caused by operation of said machine.

38. In a coil winding machine in which coils are wound from wire contained on a spool, means for positively driving said spool to feed wire to

60 said machine, including means for preventing rotation of the spool independent of the power supplied by said driving means, and means responsive to the pull on said wire by operation of said machine for regulating the speed of said driving means.

39. The method of winding a resistance wire on a core or support to form a resistance element, which consists in rotating the support to wind the wire thereon, positively feeding the wire to

70 the support independent of the pull on the wire caused by the winding operation, maintaining a section of the wire between the support and feeding means under a varying tension which increases or decreases depending on whether the winding speed or the rate of feed is the higher,

23

and regulating the rate of feed responsive to changes in the tension in said section.
